UNITED STATES PATENT OFFICE.

ANTONIO V. BRUN, OF OAKLAND, CALIFORNIA.

WINDOW-SCREEN.

1,234,105.

Specification of Letters Patent. Patented July 17, 1917.

Application filed May 1, 1916. Serial No. 94,824.

To all whom it may concern:

Be it known that I, ANTONIO V. BRUN, a citizen of the United States, residing at Oakland, in the county of Alameda and 5 State of California, have invented certain new and useful Improvements in Window-Screens, of which the following is a specification.

This invention relates to improvements in 10 window screens and has as its object the construction of a screen which will cover the entire window, but when not in use is rolled out of sight and does not obstruct the vision through the window.

15 Another object of my invention is to provide a screen which may be attached to windows of ordinary construction with the minimum expense and trouble; and

20 Lastly my invention aims to provide an improved screen which costs no more than the ordinary fixed or stationary screen as it is used on the outside of the window.

25 With these and other objects in view the invention consists in the novel construction, combination and arrangement of parts herein described, and more specifically pointed out in appended claims.

Reference being had to accompanying 30 drawing forming a part of this specification, Figure 1 is a view in vertical section through the window and screen.

Fig. 2 is a view in section through a window having a modified form of the screen.

Fig. 3 is a view in front elevation of a 35 window showing my improved screen attached thereto.

Fig. 4 is an enlarged view in section through the window frame showing the track in which the screen moves.

40 Fig. 5 is a similar view of the track for the modified form.

Fig. 6 is a view in section through the lower end of the screen.

Fig. 7 is an enlarged fragmentary view of 45 the lower corner of the screen.

Referring to corresponding parts in the several views by the same numerals of reference, 1 denotes my improved screen which has a width equal to the window and a 50 length sufficient to entirely close the same. This screen is attached to a roller 2 of the type used in the roller window shades, this roller being mounted as hereinafter described. To the lower end of the screen is 55 attached a double cloth of leather piece 10 which is stitched as at 12 forming two lon-

gitudinal pockets 13 and 16 in which are held the strip 4 and a bar 11 respectively. The latter bar is provided with projecting ends which engage the trackways that act 60 as guides for the edges of the screen. The side edges of the screen are provided with a binding 14 to eliminate wear and cause it to wind better upon the roller 2. In the binding 10 is provided one or more holes 65 15 suitably reinforced as by a buttonhole stitch.

A trackway 5 is attached to the window stop on each side, and extends upwardly to a point adjacent the top of window. The 70 screen surrounding the roller 2 is provided with the cylindrical casing 6, having an opening 7 on the bottom, which at the side forms a substantial continuation of the trackway 5. The window stool is provided with hooks 8, the bent end of which is adapted to engage through the openings 15 above the wooden strip 4, thereby holding the screen in its lower position.

The modified form of trackway shown in 80 Fig. 5, is used when the screen roller is attached to the head casing of the window as shown in Fig. 2. This trackway is a Z-bar shape so that when one leg is attached to the window casing a groove 9 is 85 formed in which the screen and rod 11 are adapted to slide.

In the form shown in Fig. 2 the brackets 18 for the window shade 17 are spaced a sufficient distance apart to enable the screen 90 to slide therebetween and the roller may be mounted upon brackets 19 and the casing 6 omitted. In the form shown in Fig. 1 the roller is mounted directly in the end plates of the casing, the one end of the casing 95 having a cap 6' to permit the insertion of the screen.

The operation is as follows: When the window is open at the top, the screen is pulled down to the top of the upper sash, whereby the opening is entirely screened and yet an unobstructed view is had through the glass. In case it is desired to have the lower sash raised then the screen is pulled down until the rod 16 rests on the window stool, thereby effectively screening the entire window. With casement windows the screen is entirely unwound from the roller and fastened to the sill by means of hooks 8. When it is desired to close the windows 110 or otherwise change the opening, this may easily be accomplished by unhooking the

lower part of the screen and allowing the same to be wound upon the roller in the manner of the ordinary shade.

In the modified form shown in Fig. 2, the 5 roller is mounted above the shade roller 17, thereby permitting the screen to pass between the brackets 18 on which the shade roller is supported. The edges of the screen are held within the grooves 9 formed by the 10 modified form of trackway shown in Fig. 5 and the window casing, thus preventing the entrance of insects around the sides. In the modified form, in order to provide an entirely insect proof screen, it is necessary at 15 all times when the window is open, to have the lower strip 4 resting on the window stool. This form, is cheaper to manufacture and install, but otherwise is as efficient in operation.

20 While I have shown the preferred embodiment of my invention, it will be understood that minor changes may be made in detail and design without departing from the spirit of the invention.

25 I claim as new and wish to cover by Letters Patent:—

1. A window screen comprising a roller, a casing around said roller having a tangentially disposed longitudinal slot, grooved 30 guideways attached to the sides of said window having their grooves alining with the slot in said casing, a screen of flexible material attached to said roller, an extension on the bottom of said screen of relatively 35 non-porous material said extension having traverse pockets therein, and bars in said pockets having their ends engaging said guideways.

2. A window screen comprising a roller 40 pivotally mounted at the top of the win-

dow, a screen of flexible fabric material attached to said roller, a guideway for the edge of said screen attached to each side of said window, a reinforcing binding attached to each edge of said screen and engaging the adjacent guideway, an extension of relatively nonporous material attached to the bottom of said screen and having pockets formed therein, bars in said pockets engaging said guideways and means for holding said screen in its extended position. 45

3. A window screen comprising a roller a casing around said roller having a slot in the bottom, grooved guideways attached to the sides of said window the grooves of 50 said guideway alining with the slot in said casing, a screen of flexible fabric attached to said roller, a reinforcing binding on the edges of said screen, an extension on the bottom of said screen having pockets formed 55 therein, stiffening bars extending through said pockets with their ends engaging said guideways, said extension having openings therein, and hooks adapted to engage said openings secured to the sill of said window. 60

4. A window screen comprising a substantially cylindrical casing having a tangentially disposed longitudinal slot, end plates on said casing one of which is removable, a roller pivotally mounted in said 65 end plates, grooved guideways attached to the sides of said window having their grooves alining with the slot of said casing, a screen of flexible material attached to said 70 roller, an extension of relatively impervious material on the bottom of said screen having transverse pockets, and bars in said pockets 75 adapted to engage said guideways.

In testimony whereof I affix my signature.

ANTONIO V. BRUN.
